UNITED STATES PATENT OFFICE.

MARTIN LUTHER DUNNAM, OF MERIDIAN, MISSISSIPPI.

FEED-WATER HEATER.

1,287,922.

Specification of Letters Patent. Patented Dec. 17, 1918.

Application filed August 15, 1918. Serial No. 250,010.

To all whom it may concern:

Be it known that I, MARTIN L. DUNNAM, a citizen of the United States, residing at Meridian, in the county of Lauderdale and 5 State of Mississippi, have invented certain new and useful Improvements in Feed-Water Heaters, of which the following is a specification.

This invention relates to combined condensers and feed-water heaters of the type shown in Letters-Patent No. 1,076,410, granted to me October 21, 1913, and has for its object the provision of simple and efficient means whereby the water will be 10 thoroughly heated before entering the condenser and also to improve the construction of the condensing chamber.

The invention is illustrated in the accompanying drawings, in which—

20 Figure 1 is a vertical longitudinal section of an apparatus embodying my present improvements;

Fig. 2 is a horizontal section on the line 2—2 of Fig. 1;

25 Fig. 3 is an end elevation;

Fig. 4 is a transverse vertical section.

In carrying out my invention, I employ a casing which is substantially inverted U-shape in cross-section. In forming the casing, I take a rectangular blank of sheet metal or other suitable material and double the same upon itself longitudinally so that when set up on its side edges it will present an arched top 1 and vertical sides 2.

30 The lower edges of this outer casing wall may be connected by a bottom plate 3 and the ends are closed by headers, indicated at 4 and 5. Above the bottom plate 3, I provide a partition consisting of a series of

40 troughs or flues 6 extending from end to end of the casing in parallel relation and having their sides integrally or otherwise intimately connected, as shown at 7, thereby providing a series of alternating troughs 45 to contain the water admitted into the condenser, as shown at 8, and flues or passages 9 through which the heat for raising the temperature of the water may pass. Heat from the boiler furnace may be admitted

50 into the space between the bottom 3 and the partition 6 or a grate 10 may be provided at the front end of said space, as illustrated. In either event, a flue 11 will be provided at the back of the casing to 55 carry the waste heat off to any point of discharge. Upon the front header will be pro-

vided suitable doors 12 to permit access to the fire box and to the ash pit and a man-hole 13 to permit access to the interior of the condenser when necessary. Within the 60 arched portion of the casing, I provide a plurality of air tubes 14 which extend from end to end of the casing and have their ends opening through the respective headers 4 and 5, as shown. These air pipes are arranged in arcuate rows, as shown most clearly in Fig. 4, and below each row is disposed a drip plate 15 which catches the drip from the water condensing upon these tubes or pipes and directs the same into 70 troughs 16 arranged on the sides of the casing in position to catch the discharge from the lower edges of all the plates. A feed pipe 17 is arranged in a tortuous path extending through the several flues 9 and extending longitudinally of the said flues. The sections of the pipe are connected alternately at the front and rear of the condenser by branches 18, as shown most clearly 75 in Fig. 2 and the discharge end of the pipe 80 is carried inwardly through the front header 5 and preferably equipped with a spout 19 whereby the water is deposited in the adjacent trough 8. The flow through the feed pipe should be so regulated that the level of 85 the water in the condenser will remain approximately constant just at or below the bottoms of the troughs 16. From the front ends of the troughs 16, pipes 20 extend to a pump (not shown) which operates to draw 90 the water from the troughs and force it to the boiler or gang of boilers.

From the foregoing description, taken in connection with the accompanying drawings, it will be readily seen that the water, 95 which must flow through the feed pipe 17 before entering the condenser, is exposed to the direct action of the fire upon the grate 10 or the heated currents fed to the heat chamber from the boiler furnace and the 100 escape of the heated currents through the flue 11 will create a draft through the pipes or tubes 18 which will draw cool air constantly therethrough. As the water enters the condenser in a heated state it will be 105 readily vaporized within the condenser and the vapor will, of course, rise to and circulate between the several drip plates and condensing tubes and will be recon-densed by contact with said tubes so that 110 the purified water will drip onto the drip plates and be directed thereby into the

troughs 16 from which it will be drawn and fed to the boiler by the feed pumps as stated. The corrugated formation of the partition 6 which constitutes the bottom of the condensing chamber and also the roof of the heating chamber provides an extended heating surface in direct contact with the water in the condenser so that the vaporizing operation will be efficient and continuously 5 performed. The inverted U-shaped form of the casing permits the same to be very expeditiously and economically manufactured so that the cost of installing the condenser in existing plants as well as in plants to be 10 built will be minimized. The form of the casing, furthermore, provides a wider support for a condenser chamber of a given diameter than forms heretofore employed.

Having thus described my invention, what 15 is claimed as new is:

A feed-water heater and condenser comprising an inverted U-shaped casing including straight vertical sides and an arched

top, a partition secured at its side edges to the straight vertical sides of the casing, 25 said partition being constructed with longitudinal corrugations forming troughs and flues, a header closing the front end of the casing, a second header closing the rear end of the casing and having its lower end constructed to leave the space below the partition and the rear ends of the flues in the partition open, an escape flue at the rear end of the casing in communication with the flues in the partition and the space below the 30 partition, a feed pipe passing tortuously through the several flues and having one end carried inwardly through the header at the front end of the casing and provided with a spout discharging into one of the troughs, 35 means in the upper portion of the casing for condensing the vapor rising from the troughs, and means for drawing off the condensed vapor.

In testimony whereof I affix my signature. 40

MARTIN LUTHER DUNNAM. [L.S.]
